Primary Examiner — David G Muller*Assistant Examiner* — Nathan M Johnston(74) *Attorney, Agent, or Firm* — Boyle Fredrickson, SC(57) **CLAIM**

The ornamental design for an insert for a web material dispenser, as shown and described.

DESCRIPTION

FIG. 1 is an isometric view of an insert for a web material dispenser, embodying my new design;

FIG. 2 is a front elevation view thereof;

FIG. 3 is a side elevation view thereof, wherein the opposing side elevation view is a mirror image thereof;

FIG. 4 is a top plan view thereof; and,

FIG. 5 is a bottom plan view thereof.

The features shown in broken lines depict environmental subject matter only and form no part of the claimed design.
